NOZZLE

Earnest J. Dillman, Detroit, Mich., assignor to Detroit Lubricator Company, Detroit, Mich., a corporation of Michigan

Application May 10, 1935, Serial No. 20,721

7 Claims. (Cl. 299—59)

My invention relates generally to nozzles and more particularly to water discharge nozzles.

One of the objects of my invention is to provide a new and improved water discharge nozzle of the type having provision for maintaining the nozzle discharge orifice free of clogging matter.

Another object of my invention is to provide a liquid discharge nozzle having automatically operable cleaning mechanism for the discharge orifice and to provide novel pressure relief means to release trapped water in the nozzle tending to prevent operation of the cleaning mechanism.

Another object of my invention is to provide a durable nozzle structure of the above mentioned character which is efficient in operation and economical to manufacture and yet simple in construction both as regards its parts and their assembly.

The invention consists in the improved construction and combination of parts, to be more fully described hereinafter and the novelty of which will be particularly pointed out and distinctly claimed.

In the accompanying drawing, to be taken as a part of this specification, I have fully and clearly illustrated a preferred embodiment of my invention, in which drawing—

Fig. 1 is a view showing how my improved nozzle may be mounted to produce a suitable moisture spray;

Fig. 2 is a view shown in longitudinal section taken centrally through my improved liquid discharge nozzle, and

Fig. 3 is a perspective view of my nozzle as seen looking toward the discharge end thereof.

Referring to the drawing, and more particularly to Fig. 1, the numeral 1 designates generally a liquid discharge nozzle mounted on a vertical wall 2 of a receptacle 3, which receptacle has, in the present instance, an angularly disposed baffle wall 3^a against which the nozzle 1 is arranged to direct a stream of liquid, indicated at 4, to produce a fine spray or mist. Among other uses, the nozzle 1, receptacle 2 and baffle 3^a may be employed in a humidifying apparatus (not shown) for introducing moisture into air passing through the apparatus, or the nozzle and baffle may be arranged with a foodstuff display receptacle for spraying foodstuffs contained therein to keep the same in a fresh condition. In the present instance, the wall 2 of the receptacle 3 is formed with an apertured boss 5, which is internally threaded and into which is screw-threaded one end of a water supply pipe 6. The water supply pipe 6 extends through the wall 2 and

projects into the receptacle wherein it is connected to the discharge nozzle 1, which, in the present instance, is supported by the water supply pipe. The receptacle 3 is also provided with a drain pipe 6^a which opens into the receptacle through and extends downward from the bottom wall thereof. The nozzle 1 may be provided with a tubular extending portion 7, defining the inlet to the nozzle and which may be externally threaded for threading into the water supply pipe 6. A suitable fitting or packing nut 7^a may be provided to insure a leak-proof connection between the water supply pipe and the nozzle.

Referring now to Fig. 2 in which the construction of the nozzle 1 is shown, the nozzle 1 includes a sectionally constructed or two-part casing comprising, in general, a body portion or base member 8 and a removable end wall cap or closure member 9 therefor which closure member forms the discharge end of the nozzle casing. One wall of the body 1 is preferably recessed as at 10 and the inner side wall defining the recess is preferably circular in contour and stepped having a portion 11 of relatively small diameter which extends outwardly from the recessed wall 10, a relatively short distance to a point from which a portion 12 of relatively large diameter leads out of the body thus forming an outwardly facing annular shoulder 13. The portion 12, of larger diameter, may be internally threaded for receiving the externally threaded closure member 9. The closure member 9 extends into the portion 12 of larger diameter and the inner end of the closure member preferably has a reduced portion as at 13^a. Clamped between the shoulder 13 and the inner end wall of the removable closure member 9, there is a movable wall means or diaphragm 14 which is preferably a pan-shaped member having a circumferential reinforcing flange 15, preferably, the pan-shaped diaphragm 14 telescopes snugly over the inner reduced end portion 13^a of the closure member 9 and is carried thereby. One side of the diaphragm 14 cooperates with the recessed wall 10 and the inner side wall portion 11, of smaller diameter, to provide a chamber 17. The inner end wall of the closure member 9 is preferably recessed, as at 18, to provide clearance for movement of the diaphragm 14 and to also provide a bearing surface 19 around its periphery for bearing against a marginal edge portion 20 of the diaphragm. The recessed wall 18 cooperates with the inner side wall, defining the recess, and the adjacent side of the diaphragm 14 to provide a chamber 18^a. The diaphragm 14 is preferably of the type having

a circularly extending bent portion 21 spaced from the peripheral edge of the diaphragm to provide the marginal bearing portion 20, and which circular bent portion defines a central 5 movable portion or diaphragm proper 22. As is well known in diaphragms of this type, the central movable portion 22 is movable without such movement being transmitted to the marginal edge portion 20, such movement taking place in the 10 bent portion 21 and the diaphragm having a snap action when moved over center.

The closure member 9 is formed with a protuberance or extension 23, centrally thereof, which extends outwardly and preferably beyond 15 the outer wall 24 of the closure member, as shown. The outer wall of the closure member 9 is also preferably recessed as at 27, the inner side wall defining the recess preferably being tapered or flared outwardly along its entire periphery for inducing drainage of water therefrom. A plurality of apertures 26 are provided in the wall 27 and extend therethrough so that chamber 18^a is open to atmosphere to permit escape of air therefrom which otherwise if 25 trapped therein would resist outward movement of the diaphragm 14. The outer side wall of the protuberance 23 may have a hexagon or other suitable shape for gripping with a tool, such as a wrench to assemble and/or disassemble the body 1 and closure member 9.

The protuberance 23 is provided with centrally disposed bores longitudinally thereof including bore 30, which leads into chamber 18^a and bore 31 adjacent to and leading out of the outer end 35 of the protuberance, which bores are separated by an inner transverse wall 32. In the transverse wall 32, there is a centrally disposed aperture in the form of a bore 33 which is preferably in alignment with the center of the diaphragm 40 14. Carried by the diaphragm 14 and supported for reciprocal movement in the bored transverse wall 32 of the closure member 9, there is a tubular member 34. The tubular member 34 has a bore 38 leading out of the outer end and a bore 37 leading into chamber 17, the bores being separated by a transverse wall 35 having an aperture 36 centrally therethrough constituting the nozzle metering orifice. Preferably the inner wall of bore 37 tapers to the orifice 36 as at 38. The tubular member 34 may be fixed for movement 50 with the diaphragm 14 in any suitable manner. In the present instance, the tubular member 34 is formed with an external annular flange 40 the inner side of which is arranged to bear against 55 the adjacent side of the diaphragm. The diaphragm 14 is provided with a central aperture providing open communication from chamber 17 through bore 37 and the orifice 36 for the flow of water or other liquid therethrough. The inner 60 end of the tubular member 34 extends through the central aperture in the diaphragm and is peened over, as at 41, to connect the diaphragm and tubular member together. Within bore 30 there is a coil spring 42 having one end bearing 65 against the transverse wall 32 and the other end against the flange 40 of the tubular member. The spring 42 is held under compression during 70 flow of water through the nozzle by the force of the water acting against the diaphragm 14 and expands to move or flex the diaphragm inwardly upon discontinuance of water flow.

In coaxial alignment with the orifice 36 and extending from chamber 17 out of the rear of the body 1, there is a passageway which is formed, 75 in the present instance, by concentric bores 45,

46 and 47 respectively decreasing in diameter from the outer and relatively larger bore 45 to the relatively small bore 47 leading into chamber 17. Bore 46, intermediate bores 45 and 47, is internally threaded to receive an externally 5 threaded portion 50 of a cleaner member, the portion 50 also serving to close the bore 46 to the passage of liquid therethrough to bore 47. An extension portion 51, which may be integral 10 with the threaded plug 50 is of reduced diameter and extends through the bore 47 into the chamber 17 and is formed with a reduced portion 52 in the form of a pin which extends into bore 37 and is in coaxial alignment or registration with the orifice 36. Preferably the orifice 36 is only 15 slightly larger than the diameter of the cleaning pin 52 and if desired, the relative dimensions of the orifice and pin may be .0135 and .012 respectively. The outer and larger bore 45 is provided in the extension portion 1 to which the water supply pipe is connected and leading from inlet bore 45, and in this instance, from one side thereof or upwardly, there is a bore 53 which connects bore 45 with a relatively larger bore 54, the latter bore 20 preferably being angularly disposed and leading downwardly into chamber 17. The bore 54 leads out of the body toward the rear thereof and is internally threaded for receiving an externally threaded closure member or plug 55. The plug 55 is provided with a central bore 56 30 longitudinally therethrough from which extend lateral bores 57 connecting bore 56 with an annular chamber 58 formed by an annular slot 59 and the inner wall of bore 54, the annular chamber being in communication with bore 53. The outer 35 end of the plug 55 is formed with a flanged head 59 which may be hexagonal or other suitable shape, and between the flanged head and the body there may be provided a washer 60. On the inner end of the plug, there is carried a screen 40 member 61, the inner end wall of the plug being provided with a circular groove for receiving the screen member which may be secured therein such as by means of solder, as at 62.

In the body 1, there is provided a by-pass 65 45 in the form of a bore which communicates with chamber 17 and leads out of the rear wall of the body, the bore extending substantially parallel with the central bores 45, 46 and 47. The bore 65 is internally threaded to receive an externally 50 threaded tubular shaped valve seat member 66, the tubular member 66 having a head or annular flange 67 for abutting the recessed wall 10 of the body 1. The tubular member 66 has a reduced bore 68 through its head which constitutes 55 the valve seat or port and which cooperates with the conical face 70 of a needle valve 71 to control flow of liquid from chamber 17 through the by-pass passageway. Preferably the size of the valve seat and the cooperating conical face 70 of the 60 needle valve are made such that the valve projects through the head of the member 66 and beyond its end wall into chamber 17, the end of the valve being substantially pointed and extending to a point in close proximity to the diaphragm 65 when the same is in an outwardly flexed position as shown in Fig. 2.

The needle valve 71 is slidably mounted for reciprocal movement in the tubular valve seat member 66 and may be provided with a number of 70 spaced and longitudinally extending grooves 72 on its outer wall to provide passageways for the passage of water from chamber 17 when the valve 71 is in open position. The valve 71 is held 75 against its seat or in closed position during

discharge of water from the nozzle by means of a coil spring 73 under compression. The discharge end of the by-pass has a reduced bore portion 14 providing an inwardly facing shoulder 5 or seat for one end of the spring 73. The valve 71 is provided with a rearwardly extending reduced portion providing an abutment for the other end of spring 71.

The threaded portion 50 of the cleaner member 10 may be provided with a slot in its outer end for the reception of a screw driver which may be inserted in bore 45 and by means of which the cleaner member may be rotated and thus be longitudinally adjusted relative to the orifice 36, 15 as desired. The by-pass valve seat member 66 also may be adjusted longitudinally by rotating the member 66 and by such adjustment the pointed end of the valve may be positioned closer to or farther away from the diaphragm 14 as may 20 be desired.

The operation of the nozzle is as follows:

When water or other liquid is not flowing through the nozzle, the diaphragm is flexed inward and the cleaning pin extends into and 25 closes the orifice 36. When the liquid, which may be water, is turned on, it enters the inlet bore 45 from whence it passes through bore 53, annular passage 58, radial bore 57 and into the central bore 56 of the closure plug 55 and then 30 through strainer 61 into chamber 17. The pressure of the water acting against the diaphragm in chamber 17 moves or flexes the diaphragm outwardly to the position shown in Fig. 2, in which position the orifice member, carried by the diaphragm is moved relative to the pin so that the orifice is open. Water flows from chamber 17 into bore 37 of the orifice member 34 and through the orifice 36 wherein it is metered and discharged therefrom in a small jet or stream. 35 While water flows through the nozzle structure, the diaphragm and orifice member 34 are held in the outward position above mentioned and in this position the spring 42 is placed and held under compression having stored therein a potential force tending to return the diaphragm to 40 its normal or inward position. Upon discontinuance of water flow through the nozzle structure, the pressure of the water in chamber 17 decreases and the spring expands and moves the diaphragm and orifice member toward chamber 45 17. The pointed end of the valve 71, the orifice member 34 and the pin 52 are relatively arranged so that just before the orifice 36 receives and is closed by the pin 52, the diaphragm engages and unseats the valve 71. Thus the water that is trapped in chamber 17 and which would otherwise prevent inward movement of the diaphragm when the orifice 36 is closed is permitted to escape therefrom through the by-pass. The 50 pressure exerted by the water in chamber 17, opposing inward movement of the diaphragm, now being relieved by the opening of the by-pass, the diaphragm under the force of the expanding spring moves inwardly with less opposition and aids in expelling the water through the by-pass. The by-passed water is discharged from the rear end of the nozzle casing and is caught in the receptacle therebeneath from whence it drains through outlet pipe 6^a to the sewer. Upon removal or diminishing of the 55 resisting force of the water to the inward movement of the diaphragm, the diaphragm and consequently the orifice member carried thereby can return to normal position and upon doing so 60 the orifice 36 is brought into the plane of the

fixed cleaning pin which then extends through the orifice and dislodges any foreign matter which may have collected therein.

From the foregoing description it will now be apparent that I have provided a new and improved nozzle of the type having provision for maintaining the orifice free of clogging matter. By the provision of a by-pass for the escape of trapped liquid in the nozzle, it will be appreciated that the diaphragm will be permitted to return 10 to normal position and in so doing effect the cleaning of the nozzle orifice. It will also be seen that I have provided a discharge nozzle in which the diaphragm, orifice member and the actuator or spring are carried or supported by a readily 15 removable closure member whereby ready access may be had to the interior of the nozzle and to the parts thereof in the event of the necessity for adjustment, repairs or replacement of parts. Also this arrangement facilitates assembly of 20 the nozzle structure for the diaphragm and orifice member may be separately assembled and then with the spring, assembled to the closure member 9 after which the closure member and the parts carried thereby may, as a unitary 25 structure, be assembled to the body 1.

What I claim and desire to secure by Letters Patent of the United States is:

1. A device of the character described, comprising a body portion through which liquid flows 30 and having a recessed wall, a removable wall means disposed in said recess, a movable wall means clamped between the recessed wall and said removable wall means, and cooperating with said recessed wall to provide a chamber into 35 which liquid flows under pressure for discharge therefrom, said movable wall means having a normal position and being movable in one direction by the force exerted by the liquid, an orifice member carried by said movable wall means 40 and slidably supported in said removable wall means, a spring disposed in said removable wall means for moving said movable wall means and orifice member back to normal position upon cessation of flow, a cleaner member registering with 45 the orifice of said orifice member and arranged to extend thereinto upon return of said movable wall means to normal position whereby to clear said orifice of clogging matter, a by-pass for bypassing liquid from said chamber, and a valve 50 member closing said by-pass during flow of liquid and movable by movement of said movable wall means toward normal position to open said by-pass upon cessation of flow.

2. A device of the character described, comprising a casing having an internal chamber, a pressure responsive movable member sealed along its marginal portion to said casing and forming a wall of said chamber, said member having an opening therethrough, a nozzle member secured 60 to said movable member and having a discharge port communicating with said opening, said nozzle member having a portion projecting from said responsive member, means rigid with said casing and having guide means engaging said projecting 65 portion and holding said nozzle member against lateral movement, a cleaning member secured to said casing and having a portion aligned with and receiving said port, means normally acting to move said nozzle member to extend said cleaning portion through said port, said responsive member moving under force of fluid pressure in said chamber in opposition to said normally acting means to move said port away from said cleaning portion so that fluid can discharge from 70 75

said chamber, and means for admission of fluid to said chamber.

3. In a spray nozzle, a two-part casing comprising a pair of members rigidly secured and sealed together, a movable pressure responsive member within said casing and positioned between said casing members, a nozzle element having a bore therethrough, one of said casing members having lateral engagement with and supporting said nozzle element against lateral movement, said nozzle element having a portion of its bore of reduced cross-section to provide a discharge orifice, a supporting post extending longitudinally of and aligned with said bore, a 10 cleaning element comprising a rod of reduced cross-section and secured in and projecting from said post in registry with said orifice, the other of said casing members having a relief passageway extending therethrough and leading from 15 the interior of said casing, valve means operable to close said passageway, one of said elements being rigidly secured to and movable with said pressure responsive member, said casing having an inlet for supplying fluid under pressure to said 20 orifice, and a helical coil spring having one end in abutting engagement with one of said casing members and having its other end bearing against said responsive member and being held under compression therebetween to urge the 25 movable one of said elements into cooperable cleaning relation to the other of said elements and to oppose movement of said responsive member by fluid pressure, said spring being in concentric alignment with said supporting post so that lateral thrust of said spring on said responsive member and movable element will be minimized, said valve means being movable with said responsive member so that said valve means will be closed upon such relative movement of said 30 elements as will open said orifice, said valve means being moved by said responsive member under force of said spring to open said valve means prior to such relative movement of said elements as will close said orifice.

4. A device of the character described, comprising a casing including a pair of body members secured together, one of said members having a recess providing an internal chamber within said casing and having a passageway opening into and for inlet of fluid to said chamber, a flexible resilient member positioned within said chamber and sealed along its peripheral portion to said casing and forming a wall of a pressure chamber communicating with said passageway, said flexible member having a central aperture therethrough, the other of said body members having a hollow open-ended extension aligned with said aperture, said extension having an internal annular flange providing a guide means, a nozzle member secured and sealed in said aperture and extending through and guided in said guide means, a helical coil spring surrounding said nozzle member and held under compression between said flange and said flexible member to oppose movement of said flexible member by fluid pressure in said pressure chamber, said nozzle member having a discharge orifice, a supporting member carried by said one body member and projecting through said pressure chamber toward 70 said orifice, and a rod member of reduced cross-section projecting from said supporting member in alignment with and for receiving said orifice, said flexible member being movable by fluid pressure to move said orifice out of surrounding 75 relation to said rod.

5. A device of the character described, comprising a casing having an internal chamber, a pressure responsive movable member sealed along its marginal portion to said casing and forming a wall of said chamber, said member having an opening therethrough, a nozzle member secured to said movable member and having a discharge port communicating with said opening, said nozzle member having a portion projecting from said responsive member, means rigid with said casing and having guide means engaging said projecting portion and holding said nozzle member against lateral movement, a cleaning member secured to said casing and having a portion aligned with and receiving said port, means normally acting to move said nozzle member to extend said cleaning portion through said port, said responsive member moving under force of fluid pressure in said chamber in opposition to said normally acting means to move said port away from said cleaning portion so that fluid can discharge from said chamber, means for admission of fluid to said chamber, said casing having a relief passageway opening into said chamber and communicating with said fluid admission means, a valve member in and controlling said passageway and having a portion projecting into said chamber for engagement with said responsive member, and means in said passageway acting on and urging said valve member toward closed position, 30 said responsive member acting under force of said normally acting means to engage said valve projecting portion to move said valve member to open position, said responsive member being movable away from said projecting portion by fluid 35 pressure so that said last-named means can move said valve member to closed position.

6. A device of the character described, comprising a casing including a pair of body members secured together, one of said members having a recess providing an internal chamber within said casing and having a passageway opening into and for inlet of fluid to said chamber, said one body member having a relief passageway therethrough opening into said recess and having an internal shoulder, a valve seat member having a port therethrough and secured in the chamber end of said relief passageway, a valve member guided in said seat member and having a portion extending through said port, a helical coil spring positioned between said valve member and said shoulder and urging said valve member to its seat on said seat member, a flexible resilient member positioned within said chamber and sealed along its peripheral portion to said casing and forming a wall of a pressure chamber communicating with said first-named passageway, said flexible member having a central aperture therethrough, the other of said body members having a hollow open-ended extension aligned with said aperture, said extension having an internal annular flange providing a guide means, a nozzle member secured and sealed in said aperture and extending through and guided in said guide means, a helical coil spring surrounding said nozzle member and held under compression between said flange and said flexible member to oppose movement of said flexible member by fluid pressure in said pressure chamber, said flexible member acting under 70 force of said first-named spring to engage said valve member projecting portion to hold said valve member in open position, said nozzle member having a discharge orifice, a supporting member carried by said one body member and pro-

jecting through said pressure chamber toward said orifice, and a rod member of reduced cross-section projecting from said supporting member in alignment with and for receiving said orifice, 5 said flexible member being movable by fluid pressure to move said orifice out of surrounding relation to said rod and out of opposing relation to the projecting portion of said valve member so that said valve member spring can act to move said 10 valve member to close said port.

7. A spray nozzle comprising a base member having a marginal surrounding projecting flange, said member having a recess concentric with said flange, a cap member fitting within said flange, 15 a resilient flexible diaphragm positioned and clamped between said members and cooperating with said recess to provide a pressure chamber, said base member having a bore therethrough concentric with said recess, said diaphragm having an aperture therethrough aligned with said bore, an elongated supporting member secured in and closing the inner chamber end portion of said bore and extending through said aperture, a nozzle member secured in and sealing said aperture, said nozzle member having a discharge 20 orifice spaced from the plane of said diaphragm, said nozzle member receiving said supporting member, an orifice cleaning member secured to and projecting from said supporting member 25 and through said orifice, said cap member hav-

ing a hollow extension surrounding said nozzle member, said extension having guide means engaging and holding said nozzle member against lateral movement, said base member having an inlet passageway leading from said bore and opening into said recess for admission of fluid under pressure to said pressure chamber, said base member having a relief passageway therethrough opening into said pressure chamber and having an internal shoulder, a tubular valve seat member in said relief passageway and having a valve port, a valve member guided in and extending through said seat member and having a portion operable to close said port, a helical coil spring positioned in said relief passageway and held 10 under compression between said valve member and said shoulder to urge said valve member portion to closed position, said diaphragm engaging the recess end portion of said valve member, and a spring abutting said guide means and acting 15 on said diaphragm to urge said valve member to open position, said diaphragm acting by fluid pressure in said chamber to move said orifice out of surrounding relation to said cleaning member and to permit said valve member to close said 20 port, said second-named spring opposing movement of said diaphragm and acting to return said nozzle member orifice into surrounding relation to said cleaning member.

EARNEST J. DILLMAN. 30
